UNITED STATES PATENT OFFICE.

ALFRED A. FARLAND, OF PLAINFIELD, NEW JERSEY.

BANJO-HEAD.

1,251,360.

Specification of Letters Patent. Patented Dec. 25, 1917.

Application filed November 6, 1913. Serial No. 799,584.

To all whom it may concern:

Be it known that I, ALFRED A. FARLAND, a subject of the King of Great Britain, residing at Plainfield, in the county of Union 5 and State of New Jersey, have invented certain new and useful Improvements in Banjo-Heads, of which the following is a full and complete specification, such as will enable those skilled in the art to which it 10 appertains to make and use the same.

The primary object of the invention is the provision of a preferably metal head for banjos constructed in a novel manner to obtain satisfactory musical results and at the 15 same time withstand the necessary strains without the resultant breaking thereof at the edge of the banjo rim where the strain is greatest.

Another object of the invention is the 20 provision of a head which will not be affected by climatic changes, does not stretch to any great extent, and also will better stand the strain to which the banjo head must be subjected to secure the best tonal 25 results.

A further object of the invention is the provision of a head for banjos which is simple in construction, thoroughly reliable and efficient in its purpose, and also which is 30 inexpensive in manufacture. With these and other objects in view, the invention consists in the construction, combination and arrangement of parts as will be hereinafter fully described, illustrated in the accompanying drawing, and pointed out in the 35 claim hereunto appended.

In the drawing:—

Figure 1 is a plan view of the head, constructed in accordance with the invention 40 prior to the mounting thereof.

Fig. 2 is a perspective view of the same in the course of construction.

Fig. 3 is a perspective view of the finished head.

Fig. 4 is a transverse sectional view showing a modified form of head.

Fig. 5 is a similar view of a further modification.

Fig. 6 is a vertical sectional view of one 50 part of a straining hoop required in the use of the modified forms of head.

Fig. 7 is a vertical sectional view through the other part of the straining hoop.

Fig. 8 is a vertical sectional view through 55 the straining hoops united with one modified form of the head clamped therein.

Fig. 9 is an enlarged sectional detail on line 9—9 of Fig. 3.

Similar reference characters indicate corresponding parts throughout the several 60 views in the drawings.

Referring to the drawing in detail, the head for a banjo comprises a disk A made from metal, preferably number 38 gage taggers iron, the edge of which is cut into for 65 a distance at intervals radially toward its center to form bendable tongues 2, and thereafter the tongues are painted to form a coating on both sides thereof. After the paint has dried, the disk is placed on a circular 70 form 3 which is substantially coincident with the size of the disk where the shanks of the tongues merge into its periphery, and said shanks are bent down over the upper edge of the form so that their bodies depend 75 alongside it. A hoop 4 is now placed around the downturned tongues concentrically of the form, after which the tips of said tongues are bent outward and upward beneath and about the hoop 4 to form a bead 7 80 therefor which incloses the hoop. In event that the tips of the tongues 2 after the complete bending thereof project above the level or upper surface of the disk B, they 85 are cut off even therewith.

The hoop 4 is fastened to the form 3 in any desirable manner, preferably through the use of staples 5, and thereafter the disk B at the outer surface thereof is ground on a surface grinder to approximately 2/1000 90 of an inch in thickness. After this has been accomplished the said disk is removed from the form 3 by first withdrawing the staples, and then the tip of each tongue is riveted at 6 to its shank at a point above the hoop 4, as 95 best seen in Fig. 9.

Of course it is to be understood that the manner of fastening the free ends of the tongues may be varied, as the same may be fastened in any desirable manner. When the 100 tips of the tongues 2 have been fastened subsequent to the removal of the disk from the form, the head has been completed with the exception of the application of two thin coats of paint or enamel C, such as is commonly used on metal, whereupon the said head is ready for use on a banjo by placing it upon the rim thereof, the usual hoops and nuts being used for this purpose. The paint or enamel coating C is placed on both faces 105 of the disk which adds a little weight thereto and improves the tone produced thereby,

and at the same time prevents rust as well as giving an attractive appearance thereto.

In Fig. 4 there is shown a modified form of head, which is made in the form of a pan shaped body D having an annular bead 8 at its peripheral edge, the body being preferably of seamless thin sheet metal made in pan shape in any suitable manner. Confined within the annular bead 8 is a wire loop 9 which may be soldered or welded therein. The body D is fastened to the form 3 with the bottom thereof upward, and subsequently thereto the said bottom is ground to the required thickness, as hereinbefore mentioned. After the grinding of the bottom of the body D the same is painted or enameled in a similar manner as hereinbefore set forth.

In Fig. 5 there is shown a further modified form of head, which comprises a disk E made from thin sheet metal having a hollow peripheral bead 10 receiving a wire hook 11, which is suitably fastened in the bead, the disk E being ground and coated as hereinbefore set forth.

To use the disk E there is provided a sectional straining hoop which comprises the

parts 12 and 13 respectively, the same having reversely beveled outside surfaces 14, while the top edge of the part 13 is formed with an annular groove 15, and the part 12 is provided with holes 16 through which are passed screws 17 which are engaged with sockets in the part 13 for joining the sectional hoop for the clamping of the disk E between the parts 12 and 13. The screws 17 are also passed through the disk when clamped between the said parts of the sectional hoop, as shown in Fig. 8 of the drawing. The groove 15 in the part 13 of the sectional hoop receives the banjo rim.

What is claimed is:—

The herein described banjo head comprising a hoop, a flexible disk having peripheral tongues, each tongue being bent and passing around the hoop and having its tip overlapped on its shank, and fastening means permanently securing the overlapped portions to each other.

ALFRED A. FARLAND.
